DESIGN FOR A BRUSH AND PAN ASSEMBLY OR THE LIKE

Hazel V. Fox, Philadelphia, Pa.

Application November 18, 1944, Serial No. 116,439

Term of patent 7 years

(Cl. D44—18)

To all whom it may concern:

Be it known that I, Hazel V. Fox, a citizen of the United States, residing at Philadelphia, in the county of Philadelphia and State of Pennsylvania, have invented a new, original and ornamental, Design for a Brush and Pan Assembly or the like, of which the following is a specification, reference being had to the accompanying drawing, forming a part thereof.

Figure 1 is a face view of a brush and pan assembly of my new design, showing the brush nested in the pan.

Figure 2 is an end view of the brush and pan

assembly, the view being taken from the right of Figure 1.

Figure 3 is a face view of the brush shown in Figures 1 and 2.

Figure 4 is an end view of the brush taken from the right of Figure 3.

Figure 5 is a face view of the pan shown in Figures 1 and 2.

I claim:

The ornamental design for a brush and pan assembly or the like, substantially as shown.

HAZEL V. FOX.
